DRIER

Abe G. Samuels, Rochester, N. Y., assignor to
Samson-United Corporation, Rochester, N. Y.

Application July 22, 1935, Serial No. 32,493

4 Claims. (Cl. 34—26)

This invention relates to electric hair dryers and has for one of its objects to provide a novel form of casing and mounting for such a drier.

A further object of this invention is to provide 5 the drier with a novel form of fan mechanism for creating the air current for the drier.

Another object of this invention is to so construct the entire mechanism of the drier that its weight is axially balanced in a cylindrical housing so as to facilitate an easy handling thereof.

All these and other objects and attendant advantages will become more readily apparent from the detailed description thereof which follows, reference being had to the accompanying drawings in which—

Figure 1 is a side elevation of the hair drier.
Figure 2 is a front elevation thereof.

Figure 3 is a longitudinal sectional view of the drier.
Figure 4 is a cross section of the casing taken on the line 4x—4x of Figure 3 and an end elevation of the drying mechanism within the casing.

In the several figures of the drawing like reference numerals indicate like parts.

The hair drier construction forming the subject matter of my present invention is constructed so as to be axially balanced within a tubular casing so that in holding the drier by a handle 30 the weight thereof will be equally distributed on both sides of the handle at the end thereof with the center of gravity of the apparatus in a plane with the handle and the axis of the casing.

This is accomplished by a mechanism which 35 uses a pair of fans 1, 1 for creating the current of air for the drier. These fans are mounted on the armature shaft 2 with the armature located between them. The armature rotates between the poles 3 and 4 located at one end of the rectangular horizontally arranged field structure of the motor with its field winding 5 located at the other end thereof. The field of the motor is centrally and axially mounted within the tubular casing 6 near the closed end thereof so as to 40 have its armature rotate at right angles to the axis of the casing at a point intermediate the ends thereof.

As illustrated, the fans are of a type which 45 operate to draw the air toward the center of the fan and then force the air laterally thereof. The inlet openings 7 in the casing are located so as to be in line with the center of the fans so as to efficiently draw the air into the casing and then force it forwardly past the heating unit 8 to be 50 heated thereby. The heating unit is mounted

centrally of the housing and provides a partial partition therein so that the current of air which flows past each side of the unit is heated first and then forced out thru the outlet 9 in the forward end thereof.

In this way the weight of the mechanism of the drier is equally distributed on each side of the longitudinal axis of the housing so that any handle, as for example the handle 10, used for handling the drier and suitably attached to the housing thereof, will have the weight of the drier uniformly supported on each side thereof. This makes for ease in handling and operating the drier so that the operator thereof will not be fatigued in the use of it.

I claim:

1. In a drier the combination of an elongated tubular casing closed at one end and having an outlet at the other end, an electric motor comprising a substantially U shaped magnet arranged in the closed end of said casing, an armature mounted to rotate between the ends of said field magnet transversely of the casing, an armature shaft extending from each end of said armature, a fan mounted on each end of said armature shaft so as to be located on each side of said field magnet, said tubular casing having an inlet in the side thereof substantially in line with the axis of rotation of each of said fans, and a heating unit in front of said motor and mounted axially in said casing.

2. In a drier unit, a substantially tubular casing provided with an outlet aperture in one end thereof, an electric motor within said casing and comprising a substantially U-shaped field magnet and an armature mounted between the legs of said field magnet, said armature being provided with a shaft and extending transversely of said casing, a pair of fans carried on the ends of said shaft respectively and on opposite sides of said armature, said casing being provided with intake apertures in register with said fans, said U-shaped magnet extending into the end of said casing opposite said outlet end thereof, and electric heating means positioned in said casing between said fans and said outlet.

3. In a drier unit, a substantially tubular two-piece casing comprising a pair of mutually engageable pieces and means for retaining said pieces in locking engagement to form a joint transverse of said casing, one of said pieces having an end provided with an outlet aperture and the other of said pieces having a closed end, an electric motor mounted within said casing and extending longitudinally of said casing within

both pieces thereof and comprising a substantially U-shaped field magnet and an armature mounted between the legs of said field magnet, said armature being provided with a shaft and 5 extending transversely of said casing, a pair of fans carried on the ends of said shaft respectively and on opposite sides of said armature, said casing being provided with intake apertures in register with said fans, said U-shaped magnet 10 extending longitudinally into the closed end of the closed one of said pieces of said casing, and

electric heating means positioned in said casing between said fans and said outlet.

4. The subject matter of claim 3, said drier unit further comprising a handle carried by said casing at the point of engagement of said pieces thereof, said motor and fans and heating means being so positioned within said casing that the weight of said unit is substantially symmetrically balanced on said handle. 5
